UNITED STATES PATENT OFFICE.

FRANK E. GOULD, OF CHICAGO, ILLINOIS.

AUTOMATIC FEED-REGULATOR FOR BOILERS.

991,056.

Specification of Letters Patent.

Patented May 2, 1911.

Application filed January 10, 1907. Serial No. 351,591.

To all whom it may concern:

Be it known that I, FRANK E. GOULD, a citizen of the United States; and a resident of Chicago, in the county of Cook and State 5 of Illinois, have invented certain new and useful Improvements in Automatic Feed-Regulators for Boilers, of which the following is a specification.

This invention relates to improvements in 10 automatic feed regulators for boilers, and has for its object to provide an improved construction in devices of this character by which the feed water is introduced to the boiler continuously at whatever rate of flow 15 may be necessary to maintain the water level in the boiler practically constant, notwithstanding the variation in steam production which may be demanded of the boiler from time to time.

20 The invention consists of the matters hereinafter set forth and particularly pointed out in the appended claim and will be fully understood from the following description of the construction illustrated in the accompanying drawings, in which the figure is a sectional elevation of an automatic feed water regulator embodying my invention in one form.

In said drawing, 1 designates a float chamber from which pipes 2 and 3 lead to the boiler at points above and below the water level therein. Within this chamber is the float 4 having an upwardly extending stem 5 provided with a shoulder 6 which preferably 30 takes the form of a collar which is adjustably clamped upon the stem. This collar lies below and normally in contact with the free end of a lever 7 which is pivoted at 8 to any fixed part, such as a stud 9 that depends 35 from the upper head 10 of the chamber. The other end of the lever is connected with the stem of a valve 11 which controls a steam passage 12 that leads through suitable connections to a water supply valve 13 and a 40 leakage valve 14.

The water supply valve 13 is in the nature of a balanced valve and comprises a steam end 15 and a water end 16 connected by yoke rods 17, or other equivalent framework. 45 The water end is provided with an inlet opening 18 into which the supply pipe from the pump or water main is tapped, and an outlet opening 19 from which a discharge pipe leads to the boiler. These two openings 50 are separated by a partition 20, having top and bottom walls that are apertured in ver-

tical alignment to form seats for a pair of connected valve plates 21 and 22, which are attached to a common stem 23. This stem extends upwardly and out through a stuffing box 24 and carries at its upper end a piston 25 which fits and slides within a bore 26 in the water end 15, to which bore the steam is admitted through the pipe or passage 12, before referred to. A spring 27 is applied to 60 the under side of the piston 25, tending to normally raise it and to lift the valves 21 and 22 off their seats so as to permit water to flow from the pump to the boiler through the water end 16 of the valve. This tendency is 65 also increased by making the upper valve plate 22 somewhat larger than the lower valve plate 21, so that the pressure of the water upon them is not quite balanced, but tends to lift them off their seats and force 70 its way through.

The operation of the apparatus thus described is as follows:—The valve 11, which is preferably a needle valve or some equivalent device capable of very gradual action, 80 is constructed in such manner that it is always slightly open, so as to permit a constant escape of steam from the upper part of the float chamber into the passage 12. This steam enters the cylinder 26 and exerts 85 a pressure on the piston 25 tending to close the water valve against the action of the spring 27 and the pressure of the water on the unbalanced area of the upper valve plate 22. The collar 6 on the stem of the float is 90 so adjusted that when the water within the boiler is at its normal level, the upper surface or shoulder of the collar lightly engages the free end of the lever 7. If the water enters the boiler more readily than 95 its rate of evaporation for the time being demands, a slight raising of the water level will occur which will lift the float and oscillate the lever 7, so as to open the valve 11 still more, and this will increase the pressure upon the 100 piston 25 and tend to more nearly cut off the supply of water to the boiler. If, on the other hand, the demands on the boiler cause the water level to lower slightly, the dropping of the shoulder 6 will permit the valve 11 to close still farther, and by decreasing 105 the pressure on the piston 25, permit the water valve to open and admit an additional supply to the boiler. In this manner the water supply is made to at all times correspond in substantial exactness to the amount 110 of water being evaporated in the boiler, and

the water level is maintained without substantial variations, the raising and lowering of the float required to operate the valve 11 being almost imperceptible.

- 5 The leak valve 14 is provided as a means of enabling the workings of the apparatus to be regulated as desired, and this is accomplished by opening the valve more or less, so as to permit a greater or less leakage 10 of steam through the valve 14, and in this manner to vary the pressure on the piston 15. By adjusting the opening of this leak valve, which may be of any suitable form capable of close adjustment, the apparatus 15 may at any time be set to maintain a higher or lower water level as desired, or to maintain the same water level under different conditions of steam and water pressure, as will be understood.
- 20 A water glass 28 is shown as provided on the float chamber to enable the water level therein to be seen at any time, and a low water alarm is also provided in the shape of a whistle 29, to which steam is admitted 25 whenever, by reason of an insufficiency of water supply, the level of water becomes so low as to permit the float to drop beyond a

certain point. As herein shown, the steam passage 30 to the whistle is controlled by a valve 31 carried by a lever 32, this lever being arranged to be depressed at such times by a collar 33 on the upper end of the valve stem.

I claim as my invention:—

In a device of the character described, a float chamber, a pressure controlled feed valve, a pipe connecting the upper portion of said float chamber and the pressure chamber of said feed valve, a valve controlling the passage of steam from said float chamber to said pipe, a float in the float chamber for actuating said valve, an independent leakage port in the pipe connecting the float chamber and the pressure chamber of the float valve, and adjustable means for varying the size of said leakage port.

In testimony, that I claim the foregoing as my invention, I affix my signature in presence of two subscribing witnesses, this 4 day of January, A. D. 1907.

FRANK E. GOULD.
